STRAIGHTENING MACHINE

Henry L. Kehl, Pittsburgh, Pa., assignor to Jones & Laughlin Steel Corporation, Pittsburgh, Pa., a corporation of Pennsylvania

Application May 6, 1947, Serial No. 746,245

6 Claims. (Cl. 153—37)

1

This invention relates to a straightening machine, useful for straightening round bars or rods which have been cold drawn or rolled in coils. Heretofore in machines of this type the bar has been straightened by passing it through at least three dies mounted in a rotating spindle. The middle die is offset from the line formed by the other dies so that as the spindle rotates the offset die imparts a transverse bend to the bar. The other dies, being in the spindle, also rotate about the axis of the bar but in its line of movement as it enters and leaves the spindle and thus hold the two ends of the portion of the bar which is bent.

Although straightening machines of the above type are in general use they inherently possess certain defects and difficulties which have not heretofore been corrected. The position of the offset die in the middle of the spindle makes it difficult to adjust or replace the die. Since the longitudinal distance between the offset die and the other dies is fixed, variations in the amount of bend given to the bar can be produced only by changing the amount of offset of the offset die. This materially limits the number of different sizes of bars which one machine can process. Also, a considerable amount of skill and time is required to feed a bar into the machine and to adjust the machine at the start of an operation.

Since all of the dies rotate about the bar as it passes through the machine, there is relative movement between the dies and the surface of the bar. The dies tend to twist the bar and mar its surface, particularly if particles of the bar are picked up by the dies.

The most objectionable feature of the present machines, however, is that their design is such as to inherently limit the production of the machine. The rate at which a bar can be fed into the straightening machine for each revolution of the spindle is determined by a number of factors such as the size of the bar, the size of the coils in which the bar has been rolled, the physical properties of the bar, and the amount of bend given to the bar. In machines heretofore used it has been necessary to stop the machine in order to make adjustments necessary to obtain the maximum feed per revolution. Further, their design limits the rotation speed of the spindle,

because the offset of the central die unbalances the spindle and prevents rotation at high speeds.

I have invented a straightening machine which is so designed that a spindle remains substantially in balance even though a substantial transverse bend is given to the bar. The distance between the dies is longitudinally adjustable so that considerable variation in the amount the bars are bent as they pass through the machine can be obtained. Moreover, this adjustment can be made while the machine is in operation. One of the fixed dies is separately mounted so that access may readily be had to the offset die for adjustment or replacement.

In the accompanying drawings I have illustrated a present preferred embodiment of my invention, in which

Figure 1 is a horizontal section of my machine; Figure 2 is a vertical section along the lines II—II of Figure 1;

Figure 3 is a section along the lines III—III of Figure 2 showing the offset die in one operative position; and

Figure 4 is a section along the lines III—III of Figure 2 showing the offset die in a different operative position from that shown in Figure 3.

A straightening machine constructed in accordance with my invention comprises a frame 4 and a separate stand 5, both mounted on a suitable base 6. The frame 4 carries an entering die 8 and an offset or bending die 9. The separate stand 5 carries a delivery die 10.

The frame 4 also carries a spindle 11 and a shaft 12 for driving the spindle. The ends of the spindle 11 and of the drive shaft 12 are reduced in diameter to form necks which rotate in ball thrust bearings 13. The bearings 13 are held in the frame 4 by bearing caps 14a, 14b, 15, 16 and 17. Recesses may be cut in these caps for oil seals 18 as shown in Figures 1 and 2.

A sleeve 19 for a belt drive is keyed to the shaft 12. The shaft carries a pinion gear 20 which meshes with teeth 21 cut in the periphery of the spindle 11.

A bushing 22 threaded into the bearing cap 17 carries a second smaller bushing hardened to reduce wear, this second bushing forming the entering die 8. A bushing 23 is longitudinally threaded through the stand 5 the axis of this bushing being in line with the axis of the entering die 8. A

second and smaller bushing of hardened material is inserted in the end of the bushing 23 next to the spindle to form the delivery die 10. A hand wheel 24 is keyed to the bushing 23 at its end opposite from the die 10. Since the bushing is threaded in the stand 5, rotation of this wheel will vary the distance between the delivery die 10 and the offset die 9. A second hand wheel 25 is threaded on the bushing 23 and serves to lock the bushing in whatever position is selected. A stand 26 may also be provided to support a tube 27 which extends into the end of the bushing 23 away from the spindle 11 and serves to guide the bar after it passes through the delivery die 10.

The construction of and the manner of mounting the offset die 9 is shown in Figures 2 and 3 of the drawings. A bushing 28 is threaded into the end of the spindle 11 which is adjacent to the delivery die 10 and carries a smaller bushing of hardened material which forms the offset die 9. To reduce relative movement between the bar and the die around the circumference of the bar, the external diameter of the die 9 may be so determined that the die rotates in the bushing 28, or the die may be mounted in anti-friction bearings carried by the bushing. As shown in Figure 3, the bushing 28 is eccentrically positioned in the spindle 11 and the die 9 is eccentrically positioned in the bushing. The amount of eccentricity of the bushing with respect to the spindle and of the die with respect to the bushing is so determined that when the bushing is rotated in the spindle 180° from the position shown in Figure 3 to the position shown in Figure 4 the axis of the die 9 is brought into alignment with the axes of the entering die 8 and the delivery die 10. When the bushing is in this position a bar may be inserted through the three dies to start a straightening operation. Thereafter the bushing 28 is rotated to a position between the feeding position and the position shown in Figure 3 according to the amount of bend it is desired to give the bar. A spring-loaded plunger 29 carried by the spindle 11 holds the bushing 28 in the selected position by extending into notches 30 cut in the outer flange of the bushing 28. When the amount of offset of the die 9 is being adjusted, the plunger 29 is depressed and the bushing 28 is rotated in the spindle 11. Thereafter the plunger is released and it moves into one of the notches 30. It may be held in its inner and outer positions by a set screw 31.

It will be noted (particularly from Figures 3 and 4) that although the spindle carries an offset die which imparts a transverse bend to the bar or rod, nevertheless the spindle is substantially in balance. It is therefore possible to rotate the spindle at speeds much higher than those at which the spindles of present machines have been operated. This results in greatly increased production. By mounting the delivery die separately from the spindle I am able to provide a spindle which is shorter than those which have heretofore been used and thus obtain a more rigid construction. The separate mounting also provides easy access to the offset die for adjustment or replacement.

Since only the offset die rotates about the bar or rod upon rotation of the spindle and since this die is rotatably mounted in the spindle, there is only small relative movement between the surfaces of the die and the bar. This reduces the torque and heat produced in the material by the friction of the dies on the material. It also re-

duces the wear on the dies and prevents scratching of the material which is frequently caused by the revolving dies picking up particles from the material.

5 In my machine the degree of bending which is imparted to the bar passing through my straightening machine is not dependent upon the amount of offset of the offset die alone. The degree of bending can also be adjusted by varying the distance between the offset die and the delivery die. Moreover, this adjustment can be made while the machine is in operation.

While I have described a present preferred embodiment of my invention it is to be distinctly understood that it may be otherwise embodied within the scope of the following claims.

I claim:

1. A straightening machine for bars comprising two dies separated from each other but having their central axes in substantial alignment, a hollow spindle rotatably supported between said dies, a bushing rotatably mounted in said spindle with its center of rotation offset from the center of rotation of the spindle and from the line formed by the axes of the first two dies, means to prevent rotation of the bushing relative to the spindle, and a die carried by said bushing at a point offset from the center of rotation of the bushing a distance equal to the distance between the centers of rotation of the spindle and the bushing.

2. A straightening machine for bars comprising two dies separated from each other but having their central axes in substantial alignment, a hollow spindle rotatably supported between said dies, a bushing rotatably mounted in said spindle with its center of rotation offset from the center of rotation of the spindle and from the line formed by the axes of the first two dies, a third die eccentrically mounted in said bushing, and means for locking the bushing against rotation relative to the spindle.

3. A straightening machine for bars comprising two dies separated from each other but having their central axes in substantial alignment, means for varying the distance between the dies, a hollow spindle rotatably supported between said dies, a bushing rotatably mounted in said spindle with its center of rotation offset from the center of rotation of the spindle and from the line formed by the axes of the first two dies, means to prevent rotation of the bushing relative to the spindle, and a third die eccentrically mounted in said bushing.

4. A spindle for a bar straightening machine comprising a hollow generally cylindrically-shaped body, a bushing rotatably mounted in said body, the central axis of the bushing being parallel to but offset from the central axis of the body, a die eccentrically mounted in said bushing, and means for locking the bushing against rotation relative to the spindle.

5. A spindle for a bar straightening machine comprising a hollow generally cylindrically-shaped body, a bushing rotatably mounted in said body, the central axis of the bushing being parallel to but offset from the central axis of the body, means to prevent rotation of the bushing relative to the spindle, and a die carried by said bushing at a point offset from the central axis of the bushing a distance equal to the offset of that axis from the central axis of the spindle.

6. In a bar straightening machine having three spaced dies through which a bar may be passed and a spindle for rotating the middle die, the improvement comprising an eccentric bushing

mounted in the spindle and carrying the middle die, said bushing being rotatable relative to the spindle about an axis offset from the axis of rotation of the spindle and said middle die being freely rotatable about its own central axis relative to the bushing, and means to lock the bushing against rotation relative to the spindle, whereby the bushing is rotatable in the spindle to adjust the eccentricity of the central axis of the middle die relative to the axis of rotation of the spindle and the middle die is freely rotatable in the bushing to reduce friction between the middle die and a bar passing through it during

5

adjustment of the bushing relative to the spindle and during the bar straightening operation of the machine.
